DOLL

Stephen M. Levy, 9 E. 37th St., New York 16, N.Y.

Filed Feb. 11, 1963, Ser. No. 73,507

Term of patent 3½ years

(Cl. D34—4)

FIG. 1 is a front perspective view of a doll, showing my new design;

FIG. 2 is a rear perspective view thereof; and

FIG. 3 is a side elevational view thereof.

The characteristic feature of my design resides in the combination on the doll disclosed of the over-sized slippers permanently secured to each hand, substantially as shown.

I claim:

The ornamental design for a doll, substantially as shown and described.
